CLAIM

The ornamental design for a wireless local area network device, as shown and described.

DESCRIPTION

FIG. 1 is a front perspective view of a wireless local area network device showing my new design;
FIG. 2 is a rear perspective view thereof;
FIG. 3 is a top plan view thereof;
FIG. 4 is a bottom plan view thereof;
FIG. 5 is a left side elevation thereof;
FIG. 6 is a right side elevation view thereof;
FIG. 7 is a back elevation thereof; and,
FIG. 8 is a front elevation thereof.
